See application file for complete search history.

FIG. 1 is a front perspective view of a brush head of an oral

care implement showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate portions of the brush head of an

oral care implement that form no part of the claimed design.

The dot-dash lines define the bounds of the claimed design

and form no part thereof.
